Samuel Longley, of Cincinnati, Ohio.
Letters Patent No. 1896-Dated Feb'y. 16, 1864.
Design for a Pack of Cards.

The schedule referred to in these Letters Patent and making part of the same.

To all whom it may concern:

Be it known that I, Samuel Longley, of Cincinnati, in the County of Hamilton, and State of Ohio, have invented or produced a new and original Design for Playing Cards; and I do hereby declare that the following is a full, clear and exact description of the same, reference being had to the accompanying drawings, making a part of this specification, in which -

The figures numbered from 1 to 12, inclusive, represent the face cards of a pack of my design.

The figures numbered from 13 to 16, represent the aces of the four suits.

This design for playing cards consists in substituting for the characters hitherto used, hearts, diamonds, spades and clubs, military emblems; to wit, swords represented by a, bugles by b, cannons by c, and anchors by d, the same representing the four different branches or arms of the United States service.

Three emblems are placed or printed on the cards in the same position as the designs or characters hitherto used. In the drawings, the aces of the spot cards are only shown. It is designed that the colors, red and black, shall govern these suits as in the ordinary cards in use.

The face cards have Commanding officers upon them, the highest corresponding to Kings in ordinary cards, being generals for the land service, and commodores for the naval service, the emblem of which is the anchor. The female face cards, corresponding to Queens in ordinary cards are, for the bugles, b. Martha Washington, the corresponding male being General Washington. For the cannons Moll Pitcher is used, Columbius used for the anchor, d, and Susan Bache for the swords a.

Having thus described my invention, as best I claim as new and desire to secure by Letters Patent is -
